UNITED STATES PATENT OFFICE.

BRUNO VON BÜLTZINGSLÖWEN, OF NEW YORK, N. Y.

LIFTING-PROPELLER FOR AEROPLANES.

1,071,697.

Specification of Letters Patent. Patented Sept. 2, 1913.

Application filed September 20, 1912. Serial No. 721,450.

To all whom it may concern:

Be it known that I, BRUNO VON BÜLTZINGSLÖWEN, a citizen of the German Empire, residing in New York, in the borough of the Bronx, county and State of New York, have invented certain new and useful Improvements in Lifting-Propellers for Aeroplanes, of which the following is a specification.

This invention relates to lifting propellers for aeroplanes by which the aeroplane can be lifted in a vertical direction to any desired height without moving in forward or backward direction, and by which observations can be made from the aeroplane, explosives dropped on objects below the same, and the machine steadied, balanced and protected against sudden wind-pressure from one side or the other; and for this purpose the invention consists of a lifting propeller for aeroplanes which comprises an outer ring-shaped frame, a polygonal center-frame, a plurality of overlapping wings or blades which are pivoted to bearings of the ring-shaped and center frames, an upright shaft on said center-frame, means for imparting rotary motion to the shaft of the lifting propeller, and means for setting the individual wings or blades to suitable angles of inclination to the plane of the lifting propeller.

The invention consists further of certain details of construction and means by which the centrally-pivoted wings or blades are tilted from their horizontal overlapping position into a position at a varying angle of inclination to the plane of the lifting propeller, and the invention consists lastly of certain details of construction which will be fully described hereinafter and finally pointed out in the claims.

In the accompanying drawings, Figure 1 represents a plan-view of my improved lifting propeller for aeroplanes, together with the motion-transmitting and wing-setting mechanisms for the same, Fig. 2 is a side-elevation of Fig. 1, Fig. 3 is a vertical central section on line 3, 3, Fig. 1, Fig. 4 is a detail plan-view of two diametrically-opposite wings or blades, showing their connection with the supporting center-frame, Fig. 5 is a side-elevation of Fig. 4, in which the dotted lines show the inclined or tilted position of the wings or blades, Fig. 6 is an end-elevation of Fig. 4, and Figs. 7, 8 and 9 are various details of construction.

Similar letters of reference indicate corresponding parts throughout the different figures of the drawings.

The improved lifting propeller for aeroplanes is composed of an exterior ring-shaped frame *a*, a hexagonal center-frame *a*¹ which is keyed to an upright shaft *s*, and wings or blades *b*, the pivot-shafts *b*¹ of which turn in bearings of the outer and center frames *a*, *a*¹. The shaft *s* is supported in a neck-bearing *b*² of a horizontal arm *f*¹ of the supporting frame *f* of the aeroplane, and suspended from a collar *b*³ having antifriction-rollers *b*⁴, at the upper end of the shaft. To the lower end of the upright driving shaft *s* is applied a second collar *b*⁵ by which any vertical shifting or slipping motion of the shaft *s* is prevented. The downwardly-extended hub of the hexagonal center-frame *a*¹ is firmly keyed to the shaft *s* and attached by means of a transverse pin or key *b*⁶ to a step-bearing *b*⁷ which is supported below the center-frame *a*¹ by radial inclined straps *b*⁸ that are attached at their outer ends to the ring-shaped frame *a* and at their inner ends to a circumferential flange on the step-bearing *b*⁷, as shown clearly in Figs. 2 and 3. The middle portion of the upright shaft *s* is supported in a stationary sleeve *d* at the end of an angular bracket *d*¹ which is attached to a horizontal arm *f*¹ of the supporting frame *f*. Rotary motion is imparted to the propeller-shaft *s* from an intermediate driving shaft *s*¹, which turns in bearings of the frame *f*, by means of bevel gear-wheels *e*, *e*¹, the bevel gear-wheel *e*¹ being keyed to the upper end of the propeller-shaft *s* immediately below the arm *f*¹ of the frame *f* and adjacent to the upper end of the stationary sleeve *d*, while the bevel gear-wheel *e* is keyed to the intermediate driving shaft *s*¹. A bevel gear-wheel *e*² is keyed on the opposite end of the intermediate shaft *s*¹ and is moved in or out of mesh with the shaft *s*¹ by a clutch *c*, the shiftable member *c*¹ of which is operated by a lever-connection *c*², *c*³ with a hand-lever near the seat of the operator, so as to impart rotary motion to the intermediate shaft *s*¹ and the propeller, or interrupt the motion of the same. A bevel-pinion *e*³ is in mesh with the bevel gear-wheel *e*² and keyed to a transverse shaft *s*² by which rotary motion is transmitted to the bevel gear-wheel *e*³, the shaft *s*² being driven by an intermediate sprocket wheel.

and chain transmission (not shown) from the motor-shaft of the aeroplane. The wings or blades b are made of a double exterior clamping frame b^x and a web of suitable waterproof fabric which is tightly stretched across the clamping frame b^x . In the drawings six overlapping wings or blades and a hexagonal center-frame are shown, but it is obvious that a smaller number, such as four, or a larger number, such as eight, may be employed. In these cases the shape of the center-frame has to be made to correspond to the number of the wings or blades and has to be either of square, octagonal or other shape, according to the number of blades; each wing or blade being supported by a transverse pivot-shaft b^1 on the outer ring-shaped frame a and the inner or center frame a^1 , and set into an inclined position by pinions n^x at the inner ends of their pivot-shafts and by vertical rack-bars n^2 intermeshing therewith. The general shape of the wings or blades is oval or elongated, but straight at their inner sides, adjacent to the center-frame, and arc-shaped at their outer sides, adjacent to the outer ring-shaped frame, while the ends of the wings or blades are curved for connecting the sides, as shown in Figs. 1 and 4.

As the lifting propeller is rotated on its axis by the intermediate transmissions from the motor and driving shafts of the aeroplane, and as the shifting mechanism for the lifting of the wings or blades, whatever be the position to which it is set, has to be rotated with the lifting propeller, it is necessary to provide a grooved shiftable collar n and antifriction-rollers n^1 at the upper ends of the rack-bars n^2 , so as to diminish the friction of the rollers with the raceway formed by the groove of the shiftable collar n . The rack-bars n^2 are guided in openings o of the center-frame a^1 , and held in mesh with the pinions n^x on the inner ends of the pivot-shafts b^1 of the wings b . The collar n is located on the fixed supporting sleeve d of the upright shaft s of the lifting propeller. The collar n is shiftable, but not rotatable, on the stationary sleeve d . It is lowered by an intermediate lever-mechanism from the seat of the operator, according to the inclination which is to be given to the wings or blades b , a graduated scale (not shown) being arranged near the operating hand-lever for the shifting mechanism, so that the operator can control the desired angle of inclination of the wings or blades to the plane of the lifting propeller, and thereby the upward speed which is to be imparted to the aeroplane by the rotating lifting propeller.

The lever-mechanism by which the shifting motion is imparted to the collar n is shown in Figs. 1 and 2, and consists of a forked lever n^3 which is fulcrumed at n^4 to

downwardly-extending lugs n^5 on the stationary bracket-arm d^1 , the forked lever being provided with slots in its outer ends, which slots engage diametrical pins n^6 on the upwardly-extending hub of the grooved shiftable collar n , while the opposite end of the fulcrumed lever n^3 is connected by a pivot-link n^7 with a lever n^8 , which is fulcrumed at n^9 to the horizontal arm f^1 of the supporting frame f . The opposite end of the lever n^8 is made angular and provided with a horizontal cross-rod n^{10} , which is engaged by antifriction-rollers n^{11} located at the lower end of a connecting rod n^{12} that is actuated by a hand-lever near the seat of the operator. By lifting the connecting lever-rod n^{12} , the shiftable collar n is lowered by the action of the fulcrumed lever n^3 , so as to shift the collar n and set, by the action of the rack-bars n^2 and pinions n^x , the wings or blades b of the lifting propeller into greater or smaller inclination to the plane of the lifting propeller, according to the point on the graduated scale to which the operating hand-lever for the wings or blades is placed. By lowering the connecting lever-rod n^{12} , the collar n and rack-bars n^2 are moved in upward direction and the wings or blades returned into closed or overlapping position, as shown clearly in Fig. 1.

The shiftable collar n and the forked lever n^3 by which the same is shifted in downward or upward direction are clearly shown in detail in Fig. 8, while the tilting wings or blades and the inclined position to which they are adjusted are indicated in dotted lines in the detail Fig. 5.

The interruption of the rotary motion of the lifting propeller is accomplished by the clutch-mechanism c , c^1 which is placed on the intermediate driving shaft s^1 , and which is operated by a lever-connection from a point near the seat of the operator, so as to move the clutch in or out of mesh with the hub of the motion-transmitting gear-wheel e^2 on the shaft s^1 . When the wings or blades of the lifting propeller are in their closed or overlapping position, the lifting propeller acts as an auxiliary plane for supporting the aeroplane in the air. When rising from the ground the action of the tilting biplanes of the aeroplane, together with the action of the rotary driving propellers, is relied on for lifting the aeroplane from the ground, until it has ascended to the desired height above the ground. In the closed position, the lifting propeller acts furthermore as a balancing and steadyng device for the aeroplane, and preferably four of them, one at each corner of the supporting frame of the aeroplane, are arranged; they exert a steadyng influence on the motion of the same. When, however, the aeroplane is to be lifted vertically in upward direction, then the rotary motion of

the lifting propellers is started by throwing in the clutch-device and actuating the driving mechanisms of the lifting propellers and setting the wings or blades into more or less 5 inclined position, according to the speed at which the ascent is to be made. While ascending under the influence of the lifting propellers, the biplanes of the aeroplane have to be placed into horizontal position 10 and the motion of the driving propeller or propellers has to be interrupted, so that the ascending action is produced solely by the inclined wings or blades of the lifting propellers, which also serve to hold the aeroplane 15 at a certain point in the air. The descent is accomplished by closing the wings or blades and permitting the gradual lowering of the aeroplane by gravity, it being supported to soar in the air by the combined 20 action of the biplanes and closed lifting propellers. The lifting propellers form a very important accessory for aeroplanes as they are thereby enabled not only to ascend and descend vertically in the air, but remain still 25 at a certain elevation in the air, assist in the lifting of the aeroplanes from the ground, and exert an effective balancing and steady-
ing influence thereon.

I claim:

- 30 1. A lifting propeller for aeroplanes, comprising an outer ring-shaped frame and an inner center - frame, overlapping wings or blades pivoted to said frames, radial pivot-shafts for said wings or blades supported in 35 bearings of said frames, means for tilting said overlapping wings or blades into an inclined position relatively to the plane of the lifting propeller, and means for imparting a rotary motion to said frames and blades.
- 40 2. A lifting propeller, comprising an exterior ring-shaped frame, an inner center-frame, a plurality of overlapping wings or blades of approximately oval shape, radial

pivot-shafts for said wings or blades supported in bearings of the outer and center 45 frames, a center - shaft for the propeller, means for rotating said shaft, and means for positively setting the wings or blades into an angular position to the plane of the propeller. 50

3. The combination, with a lifting propeller for aeroplanes, comprising an outer ring-shaped frame, an inner center frame, and overlapping wings or blades having radial pivot-shafts turning in bearings of said 55 frames, of means for setting said blades into an inclined position to the plane of the lifting propeller, said means consisting of pinions at the inner ends of said pivot-shafts, shiftable rack-bars guided in openings of the 60 supporting center - frame and intermeshing with the inner pinions, a shaft keyed to the hub of the center-frame, a stationary sleeve for the center-shaft of the propeller, a shiftable collar on said sleeve, and means for im- 65 parting a shifting motion to said collar.

4. In a lifting propeller for aeroplanes, an oscillating lifting wing or blade made of an exterior double clamping frame of approximately oval shape, a web held by said 70 frame, and means for clamping the web to the frame.

5. In a lifting propeller for aeroplanes, a lifting wing or blade made of two super-posed clamping frames of approximately 75 oval shape, means for fastening the frames together, a web held between said frames, and a central pivot-shaft extending trans- versely across said frames.

In testimony, that I claim the foregoing 80 as my invention, I have signed my name in presence of two subscribing witnesses.
